COMPOSITE STRIP CONSTRUCTION

Homer G. Kellogg, Detroit, Mich., assignor to
 Motor Products Corporation, Detroit, Mich., a
 corporation of New York

Application October 4, 1937, Serial No. 167,318

4 Claims. (Cl. 293—54)

This invention relates generally to composite strips and is a continuation in part of my co-pending application, Serial No. 644,650, filed November 28, 1932.

One of the principal objects of the present invention resides in the provision of a composite louver blade for radiator grills, or the like, having a main part and having an auxiliary part in the form of a finishing strip integrally united to the main part in such a manner that rattling, or accidental disengagement of the parts is eliminated.

Another advantageous feature of the present invention which contributes materially to securing the foregoing results resides in the provision of a composite louver blade of the character set forth wherein the two parts are rolled to the desired contour and wherein the finish strip is rolled throughout its extent in intimate contacting relation with the adjacent portion of the main part.

A further object of the present invention resides in the provision of a composite louver blade wherein the two parts of the blade are not only simultaneously rolled to the desired cross sectional contour, but also wherein the finish strip is rolled in assembled relation with the main part during the interval the two sections are contoured. This arrangement not only simplifies the manufacture, but insures fashioning the finish strip to the same contour as the main part and also insures intimate, or tight engagement of the adjacent surfaces of the parts throughout the area of these surfaces.

The foregoing, as well as other objects, will be made more apparent as this description proceeds, especially when considered in connection with the accompanying drawing, wherein:

Figure 1 is a perspective view of a composite louver blade constructed in accordance with this invention;

Figure 2 is an enlarged cross sectional view taken substantially on the plane indicated by the line 2—2 of Figure 1;

Figure 3 is an enlarged cross sectional view of a slightly modified form of louver blade construction;

Figure 4 is an enlarged cross sectional view of still another form of louver blade;

Figure 5 is a plan view of a further embodiment of this invention; and

Figure 6 is a cross sectional perspective view taken substantially on the plane indicated by the line 6—6 of Figure 5.

In the embodiment of the invention illustrated

in Figures 1 and 2, the reference character 10 designates a composite louver blade having a main part 11 and an auxiliary part 12. The auxiliary part 12 is secured to one longitudinal edge of the main part 11, and is in the form of a finishing strip having a bright, or otherwise decorated exterior surface to enhance the appearance of the blade. In detail, one longitudinal edge of the blade is provided with a head 13 formed by bending the edge angularly with respect to the body thereof and flattening the same to form a substantially T-shaped contour. The finish or trim strip 12 surrounds the head 13 of the main part and the free edges of the finish strip are arranged in interlocking engagement with the inner portions of the head 13 at opposite sides of the body portion of the main part 11.

In actual practice, the main part 11 of the blade is rolled to the cross sectional contour shown in Figure 2, and the finish strip 12 is rolled on the head portion 13 of the main part. Preferably, an apparatus similar to the one disclosed in my Patent No. 2,056,675, dated October 6, 1936, is employed to effect both of the rolling operations. In this apparatus, the finish strip is rolled to a predetermined cross sectional contour at the same time the main part is rolled, and the step of rolling the finish strip on the head of the main part is a continuation of the foregoing rolling operations. In other words, when the blade reaches the final set of rolls, the finish strip is in assembled relation therewith and both parts may be fashioned to a particular longitudinal contour, if desired. As a result of the foregoing, the finish strip is in intimate surface contacting relation with the head 13 of the main part throughout the area of the adjacent surfaces of the two parts and, as a consequence, there is no tendency for the parts to become disengaged, or to rattle, during use.

In the embodiment of the invention illustrated in Figure 3, the main part 14 of the louver blade is substantially channel-shaped having parallel side walls 15 and having a substantially T-shaped head 16. The head 16 is formed by bending the side walls 15 inwardly adjacent the base of the channel and flattening the base portion to provide the T-shaped contour. As a result of the foregoing, the side walls 15 are formed with opposed longitudinally extending grooves 17 adjacent the head 16 and the finish strip 18 is assembled on the head with the longitudinal edges thereof extending into the grooves 17.

The main part 14 of the blade and the finish strip 18 are also formed by a rolling operation.

However, in this embodiment, the finish strip 18 is assembled on the base portion of the channel-shaped main part 14 prior to the flattening operation so that the free longitudinal edge portions of the finish strip are tightly gripped between the opposed walls of the grooves 17 during the rolling operation. In other words, the above construction offers the possibility of rolling the finish strip in interlocking engagement with the main part of the blade at the same time the two parts are rolled to a predetermined cross sectional contour and, as a result, the strips are firmly secured together in surface contacting relation, irrespective of variations in contour. Attention may be called to the fact that due to the working of the metal during the rolling operation, the width of the head portion 16 is less than the maximum width of the body portion of the blade and, in the present instance, the gauge of the finish strip approximates the difference in the width of the head and main portion of the part 14 so that the longitudinal edges of the finish strip will lie flush with the outer surfaces of the side walls 15.

In the embodiment of the invention illustrated in Figure 4, the main part 19 of the louver blade is substantially L-shaped having a body portion 20 and a flange portion 21. The part 19 is rolled in such a manner that the flange portion 21 is connected to the body portion 20 by means of a laterally extending bent portion 22 forming a shoulder 23. The finish strip 24 may be rolled on the exterior of the flange 21 in much the same manner as described in connection with the first embodiment of this invention and the longitudinal edges of this finish strip are rolled in interlocking engagement with the shoulder 22 and the free edge portion 25 of the flange 21.

In the embodiment of the invention illustrated in Figures 5 and 6, the main part 30 of the louver blade is curved longitudinally and is return bent at one longitudinal edge thereof in the manner designated by the reference character 31. In manufacture, the main part 30 is rolled to the cross sectional contour illustrated in Figure 6 and the finish strip 32 is rolled on the return bent longitudinal edge 31 of the main part prior to longitudinally curving the main part. As a consequence, the finish strip 32 is curved to the same degree as the main part and intimate surface contacting relation is insured, irrespective of variations in the degree of curvature.

While several embodiments of the invention have been described somewhat in detail, nevertheless, it will be noted that in each instance the finish strip is permanently connected to the main part by a rolling operation so that an intimate contacting relationship exists between the adjacent surfaces of the strip and main part of the blade. As a result of the above, each of the constructions provide a composite louver blade wherein the finish strip is an integral part of the blade and will not rattle or become disengaged during use.

What I claim as my invention is:

1. In a louver blade construction, a main part having laterally spaced side walls and having a head at one longitudinal edge connected to the body portion of said part by inwardly return bent portions forming opposed grooves, and an auxiliary part receiving said head and having the opposite edge portions positioned in said grooves in such tight contacting relation with the adjacent side walls of the grooves to prevent relative movement of said parts.

2. In a louver blade construction, a main part having laterally spaced side walls and having a head at one longitudinal edge connected to the body portion of said part by inwardly return bent portions forming opposed grooves, and an auxiliary part rolled on the head of the main part with the longitudinal edge portions tightly gripped between the walls of said grooves.

3. In a louver blade, a rolled section having laterally spaced side walls and having a head connected to the side walls by opposed return bent portions extending inwardly from the side walls, and an auxiliary rolled section receiving said head and rolled on the head with the opposite longitudinal edges extending between the sides of the grooves in such tight engagement with said sides as to prevent relative movement of said parts.

4. In a composite louver blade, a longitudinally curved part having one longitudinal edge bent upon itself, and a substantially U-shaped correspondingly curved auxiliary part receiving the return bent edge with the adjacent surfaces of the latter and auxiliary part in such intimate contacting relation as to prevent relative movement of said parts.
